UNITED STATES PATENT OFFICE.

HARRISON STAGGS, OF VALENCIA, KANSAS.

CORN-PLANTER.

SPECIFICATION forming part of Letters Patent No. 432,448, dated July 15, 1890.

Application filed April 12, 1890. Serial No. 347,628. (No model.)

To all whom it may concern:

Be it known that I, HARRISON STAGGS, a citizen of the United States, and a resident of Valencia, in the county of Shawnee and State 5 of Kansas, have invented certain new and useful Improvements in Corn-Planters; and I do declare the following to be a full, clear, and exact description of the invention, such as will enable others skilled in the art to which 10 it appertains to make and use the same, reference being had to the accompanying drawings, and to letters of reference marked thereon, which form a part of this specification.

Figure 1 of the drawings is a side view, and 15 Fig. 2 is a top plan view. Fig. 3 is a detail view.

This invention relates to certain improvements in corn-planters; and it consists of the novel construction and combination of parts, 20 as will fully appear from the following description and accompanying drawings.

In the drawings, A is a suitable frame mounted in the usual way upon an axle B, bearing upon its projecting portions at the 25 sides of said frame pairs of covering-wheels C C. The wheels of each pair are held or spaced apart by a sleeve or thimble a, slipped upon the axle B, and are themselves provided with beveled rims b, the inclination or slope 30 being upon their inner or opposite sides. The purpose of this is to enable the wheels to act as coverers in throwing or shoving the dirt toward and upon the seed. Besides, the peripheral edges will cut into any crust that may be 35 upon the surface. Furthermore, the dirt is not liable to adhere to the periphery of the wheels, they being inclined and having a tendency to pack the earth at opposite sides of a ridge thus formed over the corn.

40 D D are floats or coverers, one of each being arranged between the wheels C, of a pair, which are constructed each of an upper straight horizontal portion c and a lower section c', which, however, is extended from its 45 forward end rearward in a slight circle to its extreme rear end. This latter section is horizontal and extends beyond the contact of the wheels C with the ground or surface, preventing the catching of the wheels on said portion. The floats are preferably made of spring

55 plate metal and hinged or looped to the legs d of the shoes at their rear edges. In order to hold the plate-metal portions of the floats in their normal position are short angular blocks e, placed or secured between the converging or forward portions of said plates. Depending 60 from and secured to the under side of the lower plate-sections c' of the floats D are springs f, which bear against the rear edges of the legs of the shoes d and serve to hold the floats elevated out of working-contact with the ground when the runners are raised.

65 E E are the usual hinged or articulated front sections of the planter, to the under side of which at the forward ends are connected the forward ends of the runners g, the rear ends of which are secured to the feet of legs d.

70 F is the brake, which consists of arms e', each having a cylindric lateral stud adapted to engage the upper horizontal portion c of each float D. These arms are approximately bow or rectangular in shape, and are provided at their rear ends with fixed eyes or sleeves h, which are adjustably fitted by set or adjusting screws h' upon a common cylindrical rod i, bearing in the rear ends of the side pieces of the frame A. The adjustability of the eyes or sleeves h permits the arms e' to be readily adjusted to enable them to vary the amount of pressure it may be desired to impart to the floats D.

75 The brake F is actuated by the operator or driven from each side of the seat-supporting bar j by pressing upon the crank-levers k, fulcrumed upon a common pivot k', and connected together, and one to the brake-carrying rod i. The common pivot k' is supported in the upper rear ends of the angular bars l, bolted to the seat-supporting bar j, and which thus secures said bar in position. The connection between one crank-lever k and the brake-carrying rod i is effected by means of a pitman m, connected to said lever and to a fixed lever-bar n, connected to said rod. A rod o, connected to the bar o', uniting the two 85 crank-levers k of the hinged forward section of the planter, is connected to the rear end of a central bar q of the hinged forward section of the planter.

90 The seat-supporting bar j is secured at its 95 100

lower end between two short parallel bars j' and the front cross-piece of the frame A.

The pressure of the float upon the earth is not such as will "bake" it, as is the case with the old style of planter-wheel, where the weight of the supporting-frame and that of the rider or driver are borne by the wheel—an objection which exists to all planters heretofore used, so far as my knowledge extends. In my invention the pressure upon the float is applied and regulated at will.

Having described this invention, what I claim, and desire to secure by Letters Patent, is—

15 1. The corn-planter having the spring-metal float hung or pivoted to the rear edge of the shoe-leg and comprising an upper horizontal

portion and a lower circular inclined portion, substantially as specified.

2. The corn-planter having the float, the 20 pairs of wheels having beveled rims, and means for holding the float to its work, substantially as specified.

3. The corn-planter having the spring-metal float arranged between covering-wheels, and 25 the angular arm engaging said float and adjustable upon its support, actuated by a lever, substantially as specified.

In testimony whereof I affix my signature in presence of two witnesses.

HARRISON STAGGS.
